ABSTRACT

A vacuum control assembly for operating the breaker plate of an automotive type ignition distributor through an operating rod to provide ignition spark vacuum advance for an associated internal combustion engine. A range bracket member having an elongated slot of a length determined by the desired range of degrees of ignition spark advance is rigidly secured to the assembly mounting bracket in a location at which the slot accommodates the end portion of the operating rod which engages the distributor breaker plate and is so positioned that one end wall of the slot engages the operating end portion at the point at which the operating end portion is located with engine vacuum of a magnitude at which ignition spark vacuum advance is to be initiated.

1 Claim, 2 Drawing Figures

VACUUM CONTROL ASSEMBLY

This invention is directed to a vacuum control assembly for operating the breaker plate of an automotive type ignition distributor through an operating rod to provide ignition spark vacuum advance for an associated internal combustion engine and, more specifically, to a vacuum control assembly of this type having a range bracket member which positions the operating rod at the location at which it should be located with engine vacuum of a magnitude at which ignition spark vacuum advance is to be initiated.

As is well known in the automotive art, the breaker plate of an automotive type ignition distributor is operated by a vacuum control assembly which is usually mounted upon or close to the ignition distributor. The vacuum control assembly includes a diaphragm which is coupled to the breaker plate of the ignition distributor through an operating rod having an elongated portion secured to the diaphragm and an operating end portion extending substantially normal to the elongated portion for operatively engaging the breaker plate. Therefore, the vacuum control assembly changes the angular position of the breaker plate in response to a change of engine vacuum to which one side of the diaphragm is exposed. The diaphragm forms a seal at one side of a vacuum chamber which is in communication with the intake manifold of the associated internal combustion engine and the vacuum chamber accommodates a compression spring which opposes the pressure of ambient air against the exposed opposite side of the diaphragm. When manifold vacuum increases, the pressure of ambient air flexes the diaphragm against the bias of the compression spring and transmits motion to the breaker plate through the operating rod which is thereby revolved in a direction to produce ignition spark vacuum advance. With most, if not all, internal combustion engines, the ignition spark vacuum advance is to be initiated at a specific engine vacuum. However, due to manufacturing tolerances and the resulting differences in length of the operating rod between the several units, the point at which ignition spark advance is to be initiated may vary within the range of plus or minus one inch of mercury or plus or minus 3° of crankshaft rotation. It has been found that it is much more desirable to initiate spark vacuum advance at the precise magnitude of engine vacuum at which ignition spark advance should be initiated.

It is, therefore, an object of this invention to provide an improved vacuum control assembly for operating the breaker plate of an automotive type ignition distributor.

It is an additional object of this invention to provide an improved vacuum control assembly for operating the breaker plate of an automotive type ignition distributor wherein a range bracket member is so positioned that the operating rod which operates the breaker plate is maintained at the specific location at which it is to be located with engine vacuum of a magnitude at which ignition spark vacuum advance is to be initiated.

In accordance with this invention, a vacuum control assembly for operating the breaker plate of an automotive type ignition distributor is provided wherein a range bracket member is so positioned that the operating rod which revolves the ignition distributor breaker plate is precisely located at the point at which it is to be located with engine vacuum of a magnitude at which ignition spark vacuum advance is to be initiated.

For a better understanding of the present invention, together with additional objects, advantages and features thereof, reference is made to the following description and accompanying drawing in which:

5 FIG. 1 is a top view of a vacuum control assembly of this invention, and

FIG. 2 is a sectional view of FIG. 1 taken along line 2-2 and looking in the direction of the arrows.

Referring to the drawing, the vacuum control assembly of this invention includes a casing 10 consisting of a chamber member 11 and a cover member 14, a diaphragm 12 enclosed within casing 10 and a compression spring 15 interposed between diaphragm 12 and casing 10 for urging diaphragm 12 in a first direction 15 toward the left as looking at the drawing. Diaphragm 12 is hermetically sealed to chamber member 11 of casing 10 about the periphery thereof to provide a vacuum chamber 16. A vacuum port 18 is in communication with the inside of casing member 10. The side of diaphragm 12 opposite compression spring 15 is exposed to atmosphere, as is well known in the art. An operating rod having an elongated portion 20 secured to the diaphragm member 12 as at 21 and an operating end portion 22 extending substantially normal to the elongated portion 20 for operatively engaging the breaker plate is oscillated linearly by diaphragm member 12. A mounting bracket 25 is rigidly secured to the cover member 14 of casing member 10 and extends in a direction along operating rod 20 for mounting the vacuum control assembly upon or near the ignition distributor in a position at which the operating end portion 22 operatively engages the distributor breaker plate.

A range bracket member 30 having an elongated slot 31 of a length determined by the desired range of degrees of ignition spark vacuum advance from zero to maximum is rigidly secured to mounting bracket 25 in a location at which slot 31 accommodates the operating end portion 22 of the operating rod and is so positioned that one end wall 31a of slot 31 engages the operating end portion 22 at the point at which the operating end portion 22 is located with engine vacuum of a magnitude at which ignition spark vacuum advance is to be initiated.

During the manufacturing process, vacuum port 18 is 45 exposed to a constant vacuum of a magnitude equal to the magnitude of engine vacuum at which ignition spark vacuum advance is to be initiated in the associated engine with which the vacuum control assembly is to be used, for example 4" of mercury. This vacuum is 50 maintained until the range bracket member 30 is rigidly secured to mounting bracket 25, as by spot welds 34 and 35 for example, at a location at which end wall 31a of slot 31 thereof is in engagement with the operating end portion 22. Consequently, when vacuum is removed from port 18 and the unit assumes its relaxed position, the operating end portion 22 of the operating rod is precisely located for every one of the vacuum control assemblies at the point at which it should be located with engine vacuum of a magnitude at which ignition spark vacuum advance is to be initiated.

With most internal combustion engines, there is a predetermined maximum number of degrees of ignition spark vacuum advance required. Consequently, slot 31 of range bracket member 30 is designed to be of a 65 length which will provide ignition spark vacuum advance only between 0° and the maximum number of degrees. When the operating end portion 22 of the operating rod engages end wall 31b of slot 31, no more igni-

tion spark vacuum advance is provided.

While a preferred embodiment of the present invention has been shown and described, it will be obvious to those skilled in the art that various modifications and substitutions may be made without departing from the spirit of the invention which is to be limited only within the scope of the appended claims.

What is claimed is:

1. A vacuum control assembly for operating the breaker plate of an automotive type ignition distributor to provide ignition spark vacuum advance for an associated internal combustion engine comprising, a vacuum unit including at least a casing, a diaphragm enclosed within said casing in such a manner as to provide a vacuum chamber, a spring interposed between said diaphragm and said casing for urging said diaphragm in a first direction, a vacuum port communicating with said vacuum chamber and an operating rod oscillated

linearly by said diaphragm having an elongated portion secured to said diaphragm and an operating end portion extending substantially normal to said elongated portion for operatively engaging said breaker plate, a mounting bracket rigidly secured to said casing and extending in a direction along said operating rod, and a range bracket member having an elongated slot of a length determined by the desired range of degrees of ignition spark vacuum advance from zero to maximum which accommodates said operating end portion of said operating rod, said range bracket member, with a predetermined vacuum applied to said vacuum port, being positioned with one end wall thereof in engagement with said operating end portion of said operating rod and rigidly secured to said mounting bracket member whereby an initial compression is set in said spring.
